Assistant Examiner — Lavan M. Amerson

CLAIM

The ornamental design for a car windshield sun shade umbrella, as shown and described.

DESCRIPTION

FIG. 1 is a front, top perspective view of a first embodiment of a car windshield sun shade umbrella, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, top perspective view of a second embodiment of the car windshield sun shade umbrella;

FIG. 10 is a rear, bottom perspective view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof; and,

FIG. 16 is a bottom plan view thereof.

The broken lines in the figures illustrate portions of the car windshield sun shade umbrella that form no part of the claimed design.
